UNITED STATES PATENT OFFICE.

CHARLES MUNTER, OF NEW YORK, N. Y.

BELT-LACED GARMENT.

1,407,705.

Specification of Letters Patent. Patented Feb. 28, 1922.

Application filed December 5, 1917. Serial No. 205,625.

To all whom it may concern:

Be it known that I, CHARLES MUNTER, a citizen of the United States, residing in the city of New York, borough of Manhattan, county and State of New York, have invented a certain new and useful Belt-Laced Garment, of which the following is a specification.

This invention relates to articles of wearing apparel and more particularly to abdominal supporters with improved lacings for adjusting such supporters to the wearer.

The object of the invention is to provide a simple construction in belt-operated lacings, one which will be economical to manufacture, and will be highly efficient in its operation.

Aside from these objects, others, as well as additional features of the invention, will be apparent from the following detailed description when read in conjunction with the accompanying drawings.

In the accompanying drawings I have illustrated different practical embodiments of the invention, but the constructions there-in shown are to be understood as illustrative, only, and not as defining the limits of the invention.

Figure 1 is a side elevation showing an abdominal support, embodying the present invention wrapped about a wearer, and the belt buckled in place to pull the lacings toward it.

Figure 2 is a view similar to Figure 1, with the belt portions unbuckled, and swung rearwardly, and

Figures 3 and 4 are views corresponding to Figures 1 and 2, but showing a modified form of lacing embodying this invention.

In Figures 1 and 2 of the accompanying drawings, I have shown the preferred embodiment of my abdominal support. It will be understood that the lacing of this invention may be associated with an opening in the garment, which extends either from one edge entirely to the other, or with an opening which extends from one edge only to a position intermediate with the edges of the garment.

Referring to the construction in Figures 1 and 2, A designates an abdominal support of any well-known type, such support, for the purpose of illustration, being shown as provided at each side with an opening a, which is designed to close to a greater or less extent for the purpose of adjusting the garment

to conform to the waist measurement of the wearer. Along the rear edge b of each opening a, is a line of anchoring devices such as eyelets c, disposed at proper intervals between the upper and lower edges of the garment. Through each of these eyelets c, is adapted to be passed, one of a plurality of tapes d, each of which is secured at one end to a belt section D. The tapes d are preferably permanently secured to the belt section D, passed through the eyelets c, and are permanently secured, preferably by stitching, to the forward edge b' of the opening a. The lacings d, which close the openings a at the opposite sides of the garment, are identical, and each series of lacings is secured to a belt section as described.

One of said belt sections is, however, provided with a buckle d', so that when the belt is carried about the front of the wearer, the sections thereof may be buckled together for the purpose of placing all of the lacings d simultaneously under tension. The tension may manifestly be varied to any desired extent, depending upon the degree of tension under which the belt is placed.

It will be noted that the lacings d are of different lengths, said lengths being so proportioned that when the belt is pulled tight, all of said lacings will be placed under the same tension, so that the application of power through the belt and lacings for the purpose of adjusting the openings a to the desired degree is equalized throughout, and no one lace is placed under greater strain than any other.

In the construction just described, wherein the lacings d pass through eyelets c, it is desirable to have the garment open either in the front or back in the usual manner common to corsets or abdominal supports, through the employment of simple fasteners, hooks, or analogous devices. This, however, forms no part of the present invention, and is well-known in the art. If, however, ordinary hooks, such as are used on laced shoes, are employed in lieu of the eyelets c, and the lacings d simply hooked around their respective hooks instead of being passed through eyelets, the necessity of a front or rear opening in the garment is obviated, and both the front and back sections of the garment may be made intact and without such openings. When donning a garment embodying the hooks, the lacings d are released from the hooks, while the garment is posi-

tioned about the body, and are thereafter caught under the hooks, and the belt pulled tight in the same manner as though eyelets were employed.

5 In the construction of Figures 3 and 4, the same general scheme which underlies the construction of Figures 1 and 2, is present, but instead of each lace passing but a single time across the opening before being secured 10 to the belt section, it passes twice across the opening in the modified construction. Thus, in Figures 3 and 4, both edges *b* and *b'*, of the opening *a*, are provided with eyelets *c* at the edge *b*, and *c'* at the edge *b'*. Each lace 15 *d* is secured at the edge *b*, passes through an eyelet *c'*, is then returned across the opening *a*, and passes through an eyelet *c*, thence passing to a belt section *D* as before. If desired, the eyelets *c'* may be in the form of 20 hooks as hereinbefore described, in which case, openings for facilitating the donning of the garment are unnecessary. The construction of Figures 3 and 4 is very similar 25 to the construction of Figures 1 and 2, the chief difference being that the former is in the form of double lacing, in that it twice crosses the opening, and the latter is in the nature of single lacing, as it only crosses the opening once. The lacing of this invention 30 differs from all prior art lacings of which I am aware, in the fact that one end of each lace is permanently secured to one edge of the opening, while each lace is slidably connected with the other edge, in the form of 35 Figures 1 and 2, and has slidable connection with both edges, and permanent connection with one of them in the construction of Figures 3 and 4.

Having thus fully described the invention, 40 what I claim as new, and desire to secure by Letters Patent, is:

1. An article of wearing apparel provided with openings at the sides thereof, eyelets adjacent one edge of each side opening, a 45 pair of complementary belt sections, a plurality of laces equal in number to the number of eyelets of one side opening, each secured at one of its ends to one belt section, thence extended directly to and through one 50 of the eyelets and secured to the opposite edge of the corresponding side opening, a plurality of additional laces similarly positioned and arranged at the other side opening and secured to the other belt section, 55 whereby when the belt sections are drawn taut there is insured the placing of the desired tension on all of the laces for the purpose of simultaneously adjusting both side openings to bring the garment into conformity with the figure of the wearer.

2. An article of wearing apparel embodying a front member and a back member having their adjacent edges approaching each other at the sides of the wearer, thereby providing substantially vertical openings in the

garment, a plurality of eyelets positioned along one of the vertical edges of one of said members adjacent each of said side openings, a plurality of laces secured to the other member adjacent the other edge of each 70 of the openings, said laces thereupon being extended through their associated eyelets in the adjacent edge of the opposing member and then turned back upon themselves and their ends gathered together, and a belt section affixed to each set of gathered ends whereby through the medium of said belt sections the lacings on each side of the garment may be simultaneously pulled so as to 75 adjust the same and the garment secured to 80 the wearer.

3. An abdominal support embodying a front portion and a back portion whereby openings are provided between the adjacent edges of said portions, complementary belt 85 sections adapted to overlie the waist of the wearer and to have their free ends secured together, connections associated with said openings embodying a plurality of laces one end of each of which is secured near one 90 edge of one of the openings, said laces being thereafter slidably associated with the other edge of said opening and thence extended to and secured to one of the belt sections, a plurality of additional laces one end of each 95 of which is secured near one end edge of the other opening, said latter laces being thereafter slidably associated with the other edge of the latter opening and thence extended to and secured to the other belt section, 100 whereby, when the free ends of the belt sections are connected and are drawn about the waist of the wearer, all of said laces are placed under tension for the purpose of adjusting the openings so as to bring the support into proper configuration on the wearer.

4. An article of wearing apparel embodying two complementary body members having openings between them, a plurality of anchoring devices positioned near and along 110 the edges of one of said members adjacent each of said openings, a plurality of laces secured to the other member, said laces thereupon being extended over the anchoring devices positioned near the adjacent 115 edge of the opposing member and thereafter returned upon themselves and their ends gathered, and a belt section affixed to each set of gathered ends, said belt sections being adapted to extend across the body of the 120 wearer and to have their free ends adjustably connected, whereby, through the medium of said belt sections, the laces secured to the garment may be simultaneously pulled so as to adjust the same and the garment 125 thereby properly conformed to the wearer.

5. An article of wearing apparel embodying two complementary body members having openings between them, a plurality of anchoring devices positioned near and along 130

the edges of each of said members adjacent each of said openings, a plurality of laces secured to one of said members adjacent each of its edges, said laces thereupon being extended through the anchoring devices positioned near the adjacent edge of the opposing member and thereafter turned upon themselves and slidably associated with the anchoring devices on the edge to which they are secured and their free ends then gathered, and a belt section affixed to each set of gathered ends, whereby, through the medium of said belt sections, the laces secured to the garment may be simultaneously pulled so as to adjust the same and the garment thereby properly conformed to the wearer.

6. An abdominal support embodying a front portion and a back portion adapted to overlie the corresponding parts of the body, leaving vertically extending openings between the lateral edges of said portions at the sides of the body, a pair of complementary belt sections adapted to overlie the

waist of the wearer, connections associated with said openings embodying a plurality of laces, one end of each of which is secured to one edge of one side opening, said laces being thereafter slidably associated with both edges of said latter side opening, and thence extended to and permanently secured to one of the belt sections, a plurality of additional laces, one end of each of which is permanently secured to one edge of the other side opening, thereafter slidably associated with both edges of said latter side opening, and thence extended to and secured to the other belt section, whereby, when the belt sections are drawn taut about the waist of the wearer, all of said laces are placed under tension for the purpose of adjusting the side openings to bring the support into proper configuration on the wearer.

In testimony whereof I have signed my name to this specification.

CHARLES MUNTER
